UNITED STATES PATENT OFFICE.

SAMUEL P. WELD, OF BOND'S VILLAGE, MASSACHUSETTS.

DESIGN FOR A BOTTLE-STOPPER.

SPECIFICATION forming part of Design No. 18,406, dated June 19, 1888.

Application filed May 3, 1888. Serial No. 272,720. Term of patent 14 years.

To all whom it may concern:

Be it known that I, SAMUEL P. WELD, of Bond's Village, in the county of Hampden and State of Massachusetts, have invented and produced a new and original Design for Stoppers for Bottles, Jars, and other Vessels, of which the following is a specification.

The design consists in a bottle or other like stopper of peculiar exterior configuration, substantially as hereinafter described, and shown in the accompanying drawing, which forms part of this specification.

The figure represents an exterior longitudinal view of my newly-designed stopper.

The exterior configuration of the stopper is that of a circular bead, *b*, at top of a rounded or convex profile, beneath which is an upper body part, *B*, also of circular form, the profile of which is of ogee shape, with the convex

portion *c* of the ogee in excess of the concave portion *d* of said figure, the concave portion joining the rounded bead *b*. Below this upper body part is a lower body part, *C*, of downwardly-tapering cylindrical form in the same longitudinal axial line as the upper body part, *B*, which overhangs it as a circular head.

I claim—

The design for a stopper for bottles, jars, and other vessels herein shown and described, the same consisting of an upper circular bead of convex profile on its exterior, a circular body part, *B*, of an ogee profile on its exterior, and an additional lower circular body part, *C*, of downwardly-tapering configuration.

SAMUEL P. WELD.
